US00D948819S

(12) **United States Design Patent** (10) **Patent No.:** **US D948,819 S**
(45) **Date of Patent:** **** Apr. 12, 2022**

(54) **CLEANER FOR DUST CANISTER**

(71) Applicant: **SAMSUNG ELECTRONICS CO., LTD.**, Suwon-si (KR)

(72) Inventors: **Yeonsu Kim**, Suwon-si (KR); **Hyoungsub Choi**, Suwon-si (KR)

(73) Assignee: **SAMSUNG ELECTRONICS CO., LTD.**, Gyeonggi-Do (KR)

(**) Term: **15 Years**

(21) Appl. No.: **29/723,831**

(22) Filed: **Feb. 11, 2020**

(30) **Foreign Application Priority Data**

Sep. 3, 2019 (KR) 30-2019-0042471

(57) **CLAIM**

The ornamental design for a cleaner for dust canister, as shown and described.

DESCRIPTION

FIG. 1 is a front perspective view of a cleaner for dust canister, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view taken in the direction of line 8-8 in FIG. 2; and,

FIG. 9 is another front perspective view thereof in an environment of use.

The broken lines depict portions of the cleaner for dust canister that form no part of the claimed design. The additional broken lines in FIG. 9 show environmental structure that forms no part of the claimed design.

1 Claim, 8 Drawing Sheets
